UNITED STATES PATENT OFFICE

1,924,655

MULTIPLE TYPEWRITER SYSTEM

John H. Powers, Chicago, Ill., assignor to Robert
E. Ward, Chicago, Ill.

Application January 30, 1931. Serial No. 512,292

5 Claims. (Cl. 178—33)

An object of this invention is to provide means under the manual control of an operator for simultaneously writing portions of letters or the like. Thus a typist may place a sheet of note paper in each of the machines to be operated, address each letter in each machine to a different person or firm, and then, with said means in operation, the letter typed on the master typewriter in the usual way is simultaneously duplicated on the other typewriters which may be of any desired number, as will presently be seen. The master typewriter preferably produces a letter so that the typist can see any errors as they occur, and correct them accordingly.

Another object is to provide a number of typewriters under manual control of a single operator for use in the same vicinity, the operation being either pneumo-electric or straight electric, or the like.

Another object is to provide means for thus operating a series of typewriters at long distance and over a single wire, preferably using only a single channel of a multigraph telegraph system, such as is disclosed in the United States Patent to Baudot No. 388,244, granted August 21, 1888.

These and other objects, as will be seen, are accomplished by this invention which is in the nature of an improvement of the United States patent to MacPherson et al. No. 1,777,212, granted September 30, 1930, said present invention being fully described in the following specification and shown in the accompanying drawings, in which—

Figure 1 is a diagrammatic view showing a system arranged for long distance transmission over a single wire, the message being received and transcribed at the distant points by series of typewriters;

Fig. 2 is an enlarged elevation of the plate valve mechanism for pneumatically operating the various typewriters;

Fig. 3 is an enlarged transverse section on the line 3 of Fig. 2;

Fig. 4 is a partial longitudinal section on the line 4 of Fig. 3;

Fig. 5 is a view similar to Fig. 2 showing a modified form of plate valve mechanism showing the plates in inoperative position;

Fig. 6 is a partial view of Fig. 5 showing one of the plates moved to operative position;

Fig. 7 is an enlarged transverse section on the line 7 of Fig. 6;

Fig. 8 is an enlarged perspective view of the left end of one of the valve plates of Fig. 5 showing its actuating spring; and

Fig. 9 is a partial diagrammatic view similar to Fig. 1 but showing the mechanism as used for local work only.

The embodiment shown in Figs. 1 to 4 comprises generally a master typewriter A, a distributor B, electrically connected thereto by means of a series of switches, leads, and contacts, and a second distributor C connected to the distributor B by means of a single transmission wire, the distributor C then transmitting the message imparted to it through a series of wires D, the plate valve mechanisms E, E', each of which controls a typewriter as F, F' after the manner disclosed by the MacPherson Patent No. 1,777,212.

In the master typewriter A each of the keys, whether it represents a character, a shift for the carriage, a spacer key or the like as the key 10 of Fig. 1, is provided with a metal switch member 11 which is adapted to be moved on operation 70 of the key into electrical engagement with contacts 12, 13, 14. The contact 14 is connected in series with a battery 15, or other source of electrical energy. The contacts 12, 13 are connected through suitable leads 16, 17 with one or more insulated distributor elements 18, 19, 20, 21, 22, 23 of the distributor B.

Within these contacts lies an arcuate metal strip 24 and a brush 25 driven by means of a motor (not shown), passes over the strip 24 and the distributor elements 18, 19, etc., and making electrical contact therewith so as to pass current from the contacts to the strip. The strip in turn is connected to the transmission line 26, and this in turn connects with a similar strip 26^a of the distributor C. This distributor has a brush 25^a driven at the same speed as the distributor brush 25, and in synchronism therewith and likewise making electrical contact with the strip 26^a and the distributor elements 18^a, 19^a, etc. The brush 25^a is kept in synchronism with the brush 25 by any well known means, such as that shown and described in the patent to Baudot No. 388,244.

It will thus be seen that on closing the switch 100 10 an electrical impulse from the battery 15 will pass through the leads 16, 17, to the distributor elements 18, 21, and thence through the line 26 to the corresponding distributor elements 18^a and 21^a of the distributor C. These impulses are then 105 carried through the leads D, to the plate valve mechanisms E, E' which control the receiving typewriters F, F', as will now be described.

Referring now to Figs. 2 to 4, the plate valve mechanism is made up of stationary plates 27, 28 which are secured together by means of screws 110

or the like 29, and which are maintained a definite distance apart by means of spacers 30. Between these stationary plates are located a series of sliding valve plates 31, 32, 33, 34, 35 and 36. Each of these plates 31 to 36 inclusive has a depending arm as 31^a (Fig. 3) which is attached to the plate 31, and which carries an iron core 31^b which lies within a magnet coil 37 which is constantly actuated by means of a battery or other source of current 38, so that the plate 31^c is constantly urged to the left, as shown in Figs. 2 and 4, into contact with the stop 39 which is secured to the stationary plates 27, 28 by means of screws 40.

15 The depending arm 31^a also carries an oppositely extending portion which carries an iron core 31^c for the magnet coil 41. This coil 41 is connected through one of the leads D with its corresponding distributor element 18^a, so that when the current is sent through the distributor element 18^a the shift magnet coil 41 is energized. This shift coil is stronger than the return magnet coil 37, and on being energized causes the valve plate 31 to which it is connected to shift to the right until the plate valve is brought to rest by the stop 42, the other plate valves meantime being held in the normal retracted positions against the stop 39 by their individual return magnet coils which are constantly energized. All these coils are shown in Fig. 2, but only one is given numerals, the others being identical in construction and operation. The circuit is closed through the ground G, G'.

25 The plate 27 has a series of holes drilled therein, each corresponding to one of the switches 11, and into each hole is screwed a pipe nipple 43, and each of these is connected by a tube 44 with one of a series of pneumatics 45, each pneumatic operating one of the keys 46 or other operative members of the typewriter F, as is fully shown and described in MacPherson Patent No. 1,777,212, the keys etc., of one typewriter being connected to corresponding keys etc. on the other.

45 The valve plates 31 to 36 inclusive have a series of holes so arranged as to form a communicating passage to each of the nipples 43 for one, and only one, setting of the valve plates, all tubes 44 being closed in the normal inoperative position shown in Fig. 4. For example, to open the first tube 44 at the left, the plate 31 is moved to the right so as to bring the hole 47 in line with the holes 48 and 49. Likewise the next five tubes 44^a, 44^b etc., are opened to the air by moving one at a time the plates 32 to 36.

55 To open tube 44^c it is necessary to move simultaneously plates 31 and 32 so as to bring holes 50 into registration with holes 51 and 52. By carrying out this system of permutations and combinations with six plates, more than enough operative units can be provided to operate an ordinary typewriter, about fifty such tubes or units being required.

65 Thus it will be understood that when the system is in operation with the brushes 25, 25^a running in synchronism, the key 10 representing say the letter x of typewriter A is pressed down, the corresponding x, keys 46 of typewriter F and 46^a of typewriter F' are also pressed down as follows: Pressing down the key 10 closes the switch 11, 12, 13, 14, thereby causing current to flow from the source 15 to contacts 18 and 21, and as the brush 25 rotates current is passed through the transmission line 26, and the strip 24^a, the contacts 18^a and 21^a, and thence through leads D to the magnet coils 41 and 41^c which move both the

valve plates 31 and 34 (Figs. 2 and 4), with the result that the tube corresponding to the letter x on the typewriter F is opened to the atmosphere.

This tube when closed was under a vacuum maintained by the vacuum pump 53, which is connected to exhaust a manifold 54 and the hollow laterals 55 which carry the pneumatics 56. A series of chambers 57 are mounted side by side on the lateral 55, one for each pneumatic 56, which is mounted over it, the chamber 57 communicating with the lateral through a bleeder 58 and also with one of the tubes 44. With the tube 44 closed a vacuum in the lateral 55 will cause air in the chamber 57 to pass through the bleeder 58 so as to bring the vacuum in the lateral and the chamber to the same value.

15 A flexible diaphragm 59 in the chamber normally holds a valve 60 in a raised position so as to close an opening between the lateral 55 and a passage 61 which communicates with the pneumatic 56. This passage and pneumatic communicate with the atmosphere through an opening 62 which is normally uncovered by the valve 60 when in its raised position. When, however, the valve 60 is lowered, due to a failure of vacuum 100 in the chamber 57, the opening 62 will be closed and the lateral 55 will be in communication with the passage 61 and pneumatic 56.

This failure of vacuum in the chamber 57 occurs when one of the tubes 44 communicates 105 with the atmosphere through the opening of its corresponding passage in the plate valve E. When this occurs the air pressure in the chamber 57 presses down on the flexible diaphragm 59, shifting the valve 60, closing the opening 62, and 110 at the same time opening communication between the lateral 55 and the pneumatic 56 through the passage 61. The vacuum thus applied to the pneumatic 56 causes it to collapse, thereby drawing down the key 46 of the typewriter F through the medium of the arm 63 and the link 64.

115 The instant the plate valve E again closes, thereby breaking communication between the tube 44 and the atmosphere, the air pressure 120 within the tube 44 and the chamber 57 are bled through the bleeder 58 into the lateral 55 until the chamber and lateral are at substantially the same pressure. Thereupon the diaphragm 59 returns the valve 60 to the raised position shown 125 thereby uncovering the opening 62 and closing communication between the lateral and the passage 61. Air then rushes into the pneumatic 56 causing it to raise to the position shown, and returning the key 46 to its normal inoperative 130 position. The mechanism of this pneumatic is fully shown and described in the MacPherson patent above referred to. This same action takes place simultaneously in all of the plate valves E, E' and typewriters F, F' which are placed in 135 the circuit.

In Figs. 5 to 8 inclusive is shown a modified form of plate valve mechanism, the rest of the circuit of Fig. 1 remaining substantially the same. Referring now to Fig. 7, valve plates 31' to 36' are slidably mounted as before between stationary plates 27' and 28', and these are drilled exactly as before as illustrated in Fig. 4. The mechanism for operating these plates, however, is different. For example, each plate is provided with a notch, such as the notch 65 of plate 31', this notch adapted to be engaged by a pawl 66 which is hingedly shown at 67, the opposite end of this pawl carrying an electrical contact 68 which normally is in engagement with 145

a contact 69, the pawl 66 being normally held up so that the contacts 68, 69 are in engagement by means of a spring (not shown).

A solenoid 70 is connected at one side to the pawl 66 which is insulated from its pivot support, while the other end of the solenoid coil is connected to ground G'. The contact 69 otherwise insulated is connected through a lead 71 with one of the leads D of Fig. 1. Thus it will be seen that to release one of the plate members as 31' it is only necessary to pass a current through the lead 71, to the solenoid 70, and thence to ground. When this occurs the solenoid acting on the pawl 66 as an armature draws it down, thereby disconnecting the pawl 66 from its notch 65 in the valve plate. Thereupon the valve plate so released is urged forward by means of a spring 72, one spring acting upon each of the valve plates.

Under the action of this spring the valve plate moves forward until it encounters a metal element 73 at the right-hand end of the device (Fig. 5), which is insulated from the frame but which is connected through a wire 74 with a solenoid 75, and this in turn with a battery 76 or other source of electrical energy, the opposite end of the battery being connected to a movable armature 77 which is metal and carries a contact 78. Thus when the metal plate 31' in its movement to the right makes contact with both the metal elements 73 and 78, it completes a circuit through the armature 75 energizing the same, and thereby drawing the armature 77 to the left and restoring the plate or plates which have been moved to the right to their original position.

During this same time the pawl 66 having been drawn down by the solenoid 70 opens the contacts 68, 69; thereby breaking the circuit through the solenoid 70, the solenoid thereby releases the pawl 66 and it is returned to its original position by the spring (not shown) so as to be ready to engage the notch 65 when the plates are returned, as has just been described by the solenoid 75. All of this takes place upon the closing of the switch 11, 14 by movement of the key 10 of the master typewriter A. The form shown in Fig. 2, however, is preferred because of its speedier and more certain action.

In Fig. 9 is shown a much simpler form of system as a whole, and is much better adapted for local use, whereas the form shown in Fig. 1 is adapted for long distance transmission. In Fig. 9 the master typewriter A has a series of switches which are connected directly to the leads D' instead of through distributors B, C, as in Fig. 1. From that point on, however, the action of the two systems is the same.

By pressing a given key as 10' on the typewriter A, the same corresponding keys would be closed on the typewriters E, E'. What has been said about the typewriter keys applies also to the other necessary elements of the typewriter, such as the various shifts, the spacer bar, and the mechanism for returning the carriage, all of which are described at length in the patent to MacPherson previously referred to.

It will be understood that the pneumatic plate valves E, E', and pneumatics, electric switches and solenoids may be substituted. For example, the plates 31 to 36 may be made of insulating material with metal contacts in place of the holes, so that when a line of these buttons or contacts is formed instead of a line of holes in the present showing, an electrical impulse is transmitted

to a solenoid which replaces the pneumatic 56 for depressing the key 46. This, however, does not possess some of the advantages of the pneumatic system set forth in the MacPherson patent supra. Compressed air may also be used instead of a vacuum.

While I have shown and described but a few embodiments of my invention, it is to be understood that it is capable of many modifications. Changes, therefore, in the construction and arrangement may be made which do not depart from the spirit and scope of the invention as disclosed in the appended claims.

I claim:

1. In a device of the class described, a series of movable valve plates having holes adapted to form registering series according to the arrangement of plates, a solenoid tending to force each plate to a normally inoperative position, a solenoid adapted when energized to force the plate in the opposite direction, and means for actuating a different mechanism with each line of holes thus brought into registration. 90

2. In a device of the class described, a series of movable valve plates having holes adapted to form registering series according to the arrangement of plates, a solenoid tending to force each plate to a normally inoperative position, a solenoid adapted when energized to force the plate in the opposite direction against the action of the first solenoid, and means for actuating a different mechanism with each line of holes thus brought into registration. 100

3. In mechanism of the character described, a master typewriter, means operably connected to the controls thereof for translating movement of the controls into combinations of timed electrical impulses, a line for transmitting said impulses, a plurality of solenoids receiving said impulses, a series of valve plates having holes adapted to form registering series according to the arrangement of said plates, said solenoids moving said plates in response to said impulses, a receiving typewriter, and pneumatic means controlled by the registering of said plates for operating said receiving typewriter. 110

4. In a device of the class described, a series of movable valve plates having holes adapted to form registering series according to the arrangement of plates, a solenoid for each plate controlling its plate independently of the others, means controlling said solenoids whereby to move said plates in given combinations, means for restoring said plates to a normally inoperative position, and printing mechanisms connected with said plates whereby each line of holes thus brought into registration actuates a different one of said mechanisms. 125

5. In a device of the class described, a series of movable valve plates having holes adapted to form registering series according to the arrangement of plates, a solenoid for each plate controlling its plate independently of the others, means controlling said solenoids whereby to move said plates in given combinations, a solenoid device common to all of said plates for restoring said plates to a normally inoperative position, and printing mechanisms connected with said plates whereby each line of holes thus brought into registration actuates a different one of said mechanisms. 135
